UNITED STATES PATENT OFFICE.

HOWARD E. TRACY, OF WORCESTER, MASSACHUSETTS, ASSIGNOR TO O. S. WALKER COMPANY, OF WORCESTER, MASSACHUSETTS, A CORPORATION OF MASSACHUSETTS.

MAGNETIC CHUCK.

Application filed March 4, 1922. Serial No. 541,047.

To all whom it may concern:

Be it known that I, HOWARD E. TRACY, a citizen of the United States, residing at Worcester, in the county of Worcester and 5 Commonwealth of Massachusetts, have invented a new and useful Improvement in a Magnetic Chuck, of which the following, together with the accompanying drawings, is a specification.

10 My invention relates to magnetic chucks, and has particular reference to chucks providing a work holding face consisting of a large number of separate pole pieces, by reason of which it is peculiarly adapted for 15 the retention of thin and small pieces of work.

The object of my invention is to provide an improved arrangement and construction of the parts of a magnetic chuck of the 20 above described type that is extremely effective and durable in use and is highly desirable from a manufacturing standpoint.

In United States Patent No. 1,329,733, issued February 3, 1920, to O. S. Walker, 25 there is shown and described a magnetic chuck in which the work holding face consists of a number of separately magnetized polar sections, each section presenting a plurality of independent flush projections. 30 The several polar sections are arranged within an inclosing frame and are held in position therein by insulating material, which also fills the gaps between adjacent polar projections and thus forms, in effect, 35 an integral work holding face. While a chuck constructed as described above, is extremely effective in operation, it has been found that with the rough handling which the chucks receive from the average work- 40 man, the polar sections are liable to be broken loose from the frame, owing to the fact that it is difficult to find an insulating material possessing any great mechanical strength.

45 According to the present invention, I propose to provide an improved magnetic chuck embodying the same general principles of construction as set forth in the above described patent, but also possessing great 50 mechanical strength. My invention contemplates an improved arrangement of the parts in which a portion of the polar projections are formed integral with the frame, while the remaining polar projections are so 55 formed as to permit their being readily as-

sembled within the frame in interlocking relation, prior to the pouring of the insulating material. My invention further contemplates an improved construction in which the polar projections are magnetized by the 60 use of a minimum number of energizing coils, all as will hereinafter appear, reference being had to the accompanying drawings, in which—

Fig. 1 is a top plan view of a chuck embodying my invention. 65

Fig. 2 is a view in side elevation of the chuck shown in Fig. 1.

Fig. 3 is a transverse sectional view along the line 3—0, Fig. 1. 70

Fig. 5 is a transverse sectional view along the line 5—0, Fig. 1.

Fig. 6 is a bottom plan view of the face 75 plate, showing one-half thereof completed and the other half in process of manufacture.

Fig. 7 is a top plan view of the frame of the face plate shown in Fig. 1. 80

Fig. 8 is a transverse sectional view along the line 8—0—8, Fig. 7.

Fig. 9 is a fragmentary sectional view along the line 9—9, Fig. 7.

Figs. 10 and 11 are views in perspective, showing the form of the polar projections which are inserted in the frame shown in Fig. 7. 85

Fig. 12 is a diagrammatic view showing the relation between the polar projections shown in Figs. 10 and 11, when assembled. 90

Like reference characters refer to like parts in the different figures.

Referring to Figs. 1 and 2, the chuck generally comprises a work holding face plate 1, mounted upon a body 2, which, as best shown in Fig. 4, is provided with a back-plate seat 3 for the reception of a backplate, not shown, by means of which the chuck may be rotated. The body 2 also provides holes 4 for the reception of bolts 5, by means of which the face plate 1 may be secured thereto. 95

The body 2 is formed with a central hub portion 6 and concentric annular flanges or cores 7 and 8, between which are mounted annular coils 9 and 10. The coils 9 and 10 are adapted to be connected to a suitable source of electrical energy, not shown, through slip rings 11 and 12 carried on an 100 105 110

insulating plate 13 secured to the body 2. The coils 9 and 10 are so wound that when they are energized, the hub 6 and the outside flange 8 will be of one polarity, while the inner flange 7 will be of the opposite polarity, as indicated, the purpose of which arrangement will hereinafter more fully appear.

Referring now to Figs. 7, 8 and 9, the 10 face plate 1 consists of a casting or forging generally circular in form, and providing a central hub portion 14 from which radiate arms 15 connected by an annular rim 16, the arms 15 being undercut with respect to the hub 14 and the rim 16, as indicated at 17, so that when the plate 1 is secured to the body 2, only the hub 14 and the rim 16 will be in engagement with the hub 6 and the outer flange 8 respectively, of the 15 body 2, for a purpose to be hereinafter described. The upper surface of each arm 15 is provided with a series of spaced projections 18 extending in opposite directions and in staggered relation from the center line 20 of the arm into the spaces between adjacent arms, the projections 18 being flush with the 25 top of the hub 14 and the rim 16.

The top of the face plate 1 thus presents a plurality of concentric series of spaced 30 projections, as shown in Fig. 7, while the under side thereof presents a plurality of segmental shaped spaces 19, best shown in Fig. 6. The spaces 19 are each adapted to receive a pair of polar sections 20 and 21, each section being spaced apart from the other and from the sides of the spaces 19. As best shown in Fig. 10, the section 20 consists of a segmental portion 22, upon which is formed a plurality of upwardly and laterally extending projections 23. As best shown in Fig. 11, the section 21 similarly consists of a segmental portion 24 provided with upwardly and laterally extending projections 25. The projections 23 and 25 are 40 so arranged with respect to each other that when the sections 20 and 21 are placed side by side, as indicated in Fig. 12, the projections 23 and 25 extend in opposite directions in staggered relation. From a comparison of Figs. 7 and 12, it is apparent that the projections 23 and 25 are spaced apart from each other substantially the same distance as the projections 18.

Having thus described the various parts 50 entering into the construction of my improved chuck, the method of assembling same will now be described. The face plate 1, constructed as shown in Fig. 7, is first placed upon a suitable flat surface with the projections 18 in contact with same. A pair of sections 20 and 21 are then inserted in each of the spaces 19, with the projections 23 interlocking with and spaced from the projections 18 of the arm 15 on one side of the space 19, and with the projections 25 inter-

locking with and spaced from the projections 18 of the arm, on the other side of the same space. The opposed straight edges of each pair of sections 20 and 21 are separated by a space, indicated at 26. A pair of sections 20 and 21 having been arranged in each of the spaces 19, as shown at the right in Fig. 6, a non-magnetic insulating material, in a plastic condition, is poured into each of the spaces 19 until it completely fills the gaps between the projections 18, 23 and 25 and between the segmental portions 22 and 24 of the sections 20 and 21, after which the insulating material is allowed to harden. The top of the face plate 1 then presents the appearance shown in Fig. 1 with the several polar projections 18, 23 and 25, each separated from the other by the insulating material, all of the projections being flush with the hub 14 and the rim 16 of the plate, to present a smooth flat surface. The underside of the plate 1 then appears as shown at the left in Fig. 6, each pair of sections 20 and 21 being embedded in the insulating material within the openings 19, with only the raised seats 22^a and 24^a provided on the segmental portions 22 and 24 flush with the surface of the insulating material.

The plate 1, after machining as a unit, is then secured to the body 2 by means of the screws 5 which hold the hub 14 and the rim 16 in close engagement with the hub 6 and the flange 8 respectively, as described above, and which also serve to hold the seats 22^a and 24^a in engagement with the inner flange 7. With the above described arrangement, it is apparent that when the coils 9 and 10 are energized, the projections 18 of the base plate casting will have one magnetic polarity while the projections 23 and 25 of the sections 20 and 21 will have the opposite magnetic polarity. The face plate will then present a plurality of concentrically and radially arranged polar projections in which each projection of one polarity is substantially surrounded by projections of the opposite polarity, as indicated in Fig. 1.

From the foregoing it is apparent that I have provided an improved magnetic chuck in which the work holding face consists of a large number of separate polar projections forming a substantially unitary structure possessing great mechanical strength. The strength of the work holding face results from the fact that one-half of the separate polar projections, as well as the central hub 14 and the outer rim 16 are formed in one piece, so that almost any piece of work, no matter how small or thin, is always rigidly supported by at least one or more of the polar projections 18. Furthermore, the projections 23 and 25 of the polar sections 20 and 21 are so interlocked with the arms 15 of the face plate, that the possibility of any of the projections 23 or 25 being broken

away from the face plate, is reduced to a minimum. Consequently my improved chuck is well adapted to stand up under almost any amount of rough handling to 5 which it may be subjected, by reason of careless workmen dropping pieces of material thereon.

My improved face plate construction is also believed to be particularly advantageous in view of the fact that it permits of the several sets of polar projections being independently magnetized by the use of only two concentric coils arranged between the flanges and hub of the base plate. This arrangement materially reduces the cost of manufacture and eliminates complicated electrical connections which would be necessary for additional coils, as shown in the above mentioned Patent No. 1,329,733. 15 While the above described embodiment of my invention shows a chuck employing but two concentric coils, it will be obvious that this same type of construction is applicable to chucks in which coils in multiples of two 20 are employed, the annular flanges between the hub portion and the outer flange of the body being increased in number as desired.

While I have shown my invention in its simplest and preferred form, and as being 30 embodied in a circular chuck, it is not so limited, but may as well be embodied in chucks of different forms and shapes, without departing from the spirit and scope of my invention. I desire, therefore, that only 35 such limitations be imposed thereon as come within the scope of the appended claims.

I claim,

1. In a magnetic chuck, a work-holding face plate, consisting of a frame providing 40 a plurality of independent spaced flush surfaces arranged in rows in staggered relation and a plurality of polar sections, each providing independent spaced flush surfaces interposed between those of said frame.

45 2. In a magnetic chuck, a work-holding face plate, consisting of a frame providing a plurality of independent spaced flush surfaces arranged in rows in staggered relation and a plurality of polar sections, each providing independent spaced flush surfaces interposed between those of the said frame, the surfaces of said frame and of said sections being of opposite polarity.

50 55 3. In a magnetic chuck, a work-holding face plate, consisting of a plurality of rows of magnetized flush surfaces, each surface being of opposite polarity from the adjacent surfaces of its row and from the corresponding surfaces in adjacent rows, the surfaces of one polarity being magnetized from a unitary frame.

60 65 4. In a magnetic chuck, a work-holding face plate, consisting of a plurality of rows of magnetized flush surfaces, each surface being of opposite polarity from the adjacent

surfaces of its row and from the corresponding surfaces in adjacent rows, the surfaces of one polarity being magnetized from a unitary frame, and the surfaces of the other polarity being magnetized from a plurality of polar sections disposed within said frame. 70

5. In a magnetic chuck, a work-holding face plate, consisting of a frame providing a plurality of openings into each of which extend flush spaced projections arranged in staggered relation and a plurality of polar sections receivable in said openings and providing flush spaced projections interposed between the projections on said frame. 75

6. In a magnetic chuck, a work-holding face plate, consisting of a frame providing a plurality of openings into each of which extend flush spaced projections arranged in staggered relation and a plurality of polar sections receivable in said openings and providing flush spaced projections interposed between the projections on said frame, the projections on said frame and on said sections being of opposite polarity. 80

7. In a magnetic chuck, a work-holding face plate, consisting of a frame providing a plurality of openings into each of which extend flush spaced projections arranged in staggered relation and a plurality of polar sections receivable in said openings and providing flush spaced projections interposed between the projections on said frame, the spaces between said projections being filled with non-magnetic material to provide an integral face. 90

8. In a magnetic chuck, a work-holding face plate, consisting of a frame providing a plurality of openings into each of which extend flush spaced projections from opposite sides and a plurality of polar sections receivable in said openings and providing flush spaced projections interposed between the projections on said frame, the said polar sections being embedded in non-magnetic material within said frame, whereby said 100 flush projections provide a smooth work-holding face. 105

9. In a magnetic chuck, a work-holding face plate, consisting of a frame providing a plurality of openings into each of which extend flush spaced projections from opposite sides and a plurality of polar sections receivable in said openings and providing flush spaced projections interposed between the projections on said frame, the spaces 115 between said projections being filled with non-magnetic material and the said polar sections being embedded in non-magnetic material within said frame to provide an integral structure. 120

10. In a magnetic chuck, a work-holding face plate, consisting of a frame providing a plurality of openings into each of which extend flush spaced projections from opposite sides and a plurality of polar sections 125

- receivable in said openings and providing flush spaced projections interposed between the projections on said frame, and means for imparting opposite magnetic polarity 5 to said polar sections and to said frame.
11. In a magnetic chuck, a work holding face plate, consisting of a frame providing a central hub with arms radiating therefrom and each carrying spaced flush projections on opposite sides thereof and a plurality of polar sections receivable in the spaces between said arms and each providing spaced flush projections interposed between the projections on said arms.
12. In a magnetic chuck, a work holding face plate, consisting of a frame providing a central hub with arms radiating therefrom and each carrying spaced flush projections arranged in staggered relation and 20 a plurality of polar sections receivable in the spaces between said arms and each providing spaced flush projections arranged in staggered relation and interposed between the projections on said arms, and means for 25 imparting opposite magnetic polarity to the projections carried by said arms and said sections, respectively.

13. In a magnetic chuck, a work-holding face plate, consisting of a frame providing a central hub with arms radiating therefrom and each carrying spaced flush projections on opposite sides thereof and a plurality of polar sections receivable in the spaces between said arms and each providing spaced flush projections interposed between the projections on said arms, and means for imparting opposite magnetic polarity to the hub of said frame and to the said polar sections.

14. In a magnetic chuck, a work-holding face plate, consisting of a frame providing a central hub with arms radiating therefrom and each carrying spaced flush projections arranged in staggered relation and a plurality of polar sections receivable in the spaces between said arms and each providing spaced flush projections arranged in staggered relation and interposed between the projections on said arms, the spaces between said projections and between said polar sections and said arms being filled with non-magnetic material.

Dated this 28th day of February, 1922.
HOWARD E. TRACY.
